UNITED STATES PATENT OFFICE.

JOHN H. BROWN, OF WEST HOBOKEN, NEW JERSEY.

PROJECTILE.

1,031,320.

Specification of Letters Patent.

Patented July 2, 1912.

Application filed December 13, 1910. Serial No. 597,074.

To all whom it may concern:

Be it known that I, JOHN H. BROWN, a citizen of the United States, and resident of West Hoboken, in the county of Hudson and State of New Jersey, have invented a new and useful Improvement in Projectiles, of which the following is a specification.

My invention relates to projectiles with the object in view of providing a projectile 10 which will prevent the escape of hot gases past it and the erosion consequent upon such escape and which at the same time will prevent metal fouling.

A practical embodiment of the invention 15 is represented in the accompanying drawings in which,

Figure 1 is a view of a portion of a gun barrel including the front portion of the powder chamber and chase in proximity 20 thereto, in section, a projectile forming the subject-matter of the present invention being shown in side elevation located in the barrel in position for firing. Fig. 2 is a view of the projectile in longitudinal section, and Fig. 3 is a view of the projectile 25 in rear elevation.

The powder chamber is denoted by 1, the tapered forward end of the powder chamber by 2, a smooth bore portion of the chase in 30 which the projectile is seated, by 3, and the rifled portion of the chase by 4.

The body of the projectile is denoted by 5, and may be of any well known or approved form save only as it is modified at 35 the heel for the attachment thereto of the parts to be hereinafter described.

At a point intermediate of its length, preferably near its heel end, the body of the projectile is reduced to receive a rotating band 6. I preferably make this band broad and provide it with grooves 7 extending around its periphery. The rear end of the projectile 5 has attached thereto, in the present instance by several screws 8, a disk 45 9 of some suitable tough elastic material, such, for example, as hard or vulcanized fiber, the thickness of said disk preferably being about one-sixth the diameter of the body of the projectile. For instance, if the projectile be six inches in diameter, the thickness of the disk 9 would preferably be one inch. The central portion of the disk 9 is curved rearwardly, as shown at 10, so as to form between the face of the disk and the 50 heel end of the projectile, a chamber 11 for

the reception of a suitable lubricant. This chamber 11 preferably communicates through radial channels 12, with an annular groove 13 on the periphery of the disk 9.

In operation, when the explosive charge 60 in the powder chamber 1 is exploded, its pressure will tend to flatten the central part 10 of the disk 9, and thereby force the lubricant through the channels 12 to the groove 13 and hence to the interior surface of the 65 chase of the gun and at the same time the tough elastic disk 9 will be forced along the slope 2 and compressed so as to effectually prevent the gases from escaping past it.

As the projectile travels along the chase 70 toward the muzzle end, any slight opening between the lands of the rifled portion 4 of the chase and the rotating band 6 due to attrition between the faces of the lands and the non-elastic rotating band will be completely shut off from the gases resulting 75 from the explosive charge by the tough elastic disk 9, the elastic nature of said disk being sufficient to cause the disk to expand from its compressed condition to an extent 80 as great or greater than any wear which may take place between it, the tough elastic disk, and the interior of the chase. Furthermore, as the tough elastic disk is located at the extreme rear end of the projectile, the gases 85 will not be allowed to escape between the interior of the chase and any portion of the projectile since the said gases will be completely held back from such escape until the disk 9 leaves the muzzle. 90

While I have shown the body of the projectile 5 as solid, it is obvious that it may be a shell as well as a solid shot, and further I do not wish to limit myself to any particular thickness of the elastic disk at the 95 heel end of the projectile, nor to the radial passages leading from the lubricant chamber to the exterior of the disk, as the said lubricant may be forced outwardly between the inner face of said disk 9 and the heel 100 end of the projectile.

What I claim is:

1. A projectile provided with a disk of tough elastic material secured to its rear end and a rotating band of soft metal seated on 105 the projectile, the said disk of elastic material having a diameter greater than the diameter of the projectile including the soft metal rotating band.
2. A projectile provided with a disk of 110

tough elastic material secured to the rear end of the projectile and shaped to form a lubricant chamber between the disk and the rear end of the projectile, the said disk being provided with radial channels leading from the said chamber to its periphery.

In testimony, that I claim the foregoing

as my invention, I have signed my name in presence of two witnesses, this twelfth day of December, 1910.

JOHN H. BROWN.
